ATTORNEYS

UNITED STATES PATENT OFFICE.

STERRETT E. McNULTY, OF LOS ANGELES, CALIFORNIA.

ADJUSTABLE PHONOGRAPH REPEATER.

Application filed December 12, 1922. Serial No. 606,412.

To all whom it may concern:

Be it known that I, STERRETT E. McNULTY, a citizen of the United States, residing at Los Angeles, in the county of Los Angeles and State of California, have invented new and useful Improvements in Adjustable Phonograph Repeaters, of which the following is a specification.

My present invention relates to a repeating attachment for phonographs, and particularly to an attachment which may be adjusted to adapt the same to disc records of different diameters, and to records whose selections begin and end at different distances from the edge and from the center of the record.

It is another object of my invention to combine with an attachment of the general character mentioned a second or auxiliary device comprising an arm which may be so set as to engage the needle of a phonograph as the same shall traverse a guideway comprised in the mentioned attachment, and thereby cause the phonograph to stop, and I may construct this second or auxiliary device in such a form as to permit of its being fitted at will upon certain repeaters such as are already known and obtainable upon the market, and in use.

It is a further object of my invention to provide a repeating attachment of the character referred to in which adjustments can be simply and rapidly made, and in which there shall be such a positioning and balancing of parts that, although the normal travel of the needle of the reproducer shall not be interfered with during the rendering of any selection, nevertheless the needle shall be infallibly lifted from the record whenever the selection shall have been completely rendered, and shall thereafter be cammed either into a position suitable for a repetition of the selection or into a position adapted to stop the machine, according to the wish of the operative in charge.

It is a further object of my invention to provide an adjustable attachment of the character referred to which may be produced and sold at moderate cost, but which shall nevertheless be attractive in appearance and free from liability to derangement, all parts being preferably secured together in a unitary structure which may be mounted above any ordinary record and satisfac-

torily centered by the projecting of the usual center pin therethrough.

Further objects of my invention will appear from the following description and the claims appended thereto, it being understood that in the said description one preferred embodiment of my invention is presented by way of example, various features of my device being capable of independent use and various features of my device being capable of independent use and various modifications being possible without departure from the spirit of my invention, as the same is indicated in and by the said claims.

In general, the device upon which protection is being sought comprises a plate of sheet metal or like material adapted to be so mounted above a recording disc phonograph record that, as long as the needle of a reproducer shall be engaged by and traveling in a usual spiral round-producing groove, the said disc will be held stationary by contact of the said needle with a tractor arm mounted adjustably upon said disc, as may be fully understood from the following description and the accompanying drawings in which—

Figure 1 is a plan view of my repeating attachment.

Fig. 2 is an edge view of the same as seen from the right of Fig. 1.

Fig. 3 is an underneath or bottom plan of the angularly and slidably adjustable radial guide or tractor.

Fig. 4 is a cross section on line 4—4 of Fig. 1.

Fig. 5 is a side elevation of the automatic stop as shown in Fig. 1.

Fig. 6 is a side elevation of a stop attachment adapted to be readily applied to a form of repeater now on the market and in use.

The device as shown consists of a structure operating substantially as a bridge to lift the stylus or needle N of a phonograph as the needle approaches the inner end of a record groove and to transfer the lifted needle again to an outer position to be replaced in the leading end of the groove so that the record will be replayed. The bridge structure is embodied in the form of a segmental generally flat main plate 2 having at one end a generally radial lip 3 merging with a cross piece 4 in which is formed a center socket or ferrule 5 designed to slip

down over the usual centering pin P of the turntable T of a phonograph, which turntable is rotatable in the usual manner so as to carry the record disc D in the direction as 5 shown in Fig. 1 by the arrow thereon.

The bridge plate 2 is provided with an outer marginal guide wall or flange 2^a and an inner guide wall or flange 2^b which gradually diverge from the outermost portion of 10 the lip 3; the flanges 2^a and 2^b terminating at the end 2^c of the curved bridge plate 2. Forming an adjustable continuation of the 15 curved and flanged part of the bridge plate, there is pivotally connected as on a pivot pin 6 a segmental guide forming section 7 having a generally plane bottom and outer and inner guide walls 7^a and 7^b terminating in a slightly downwardly curved drop off end 7^c.

20 The broad object of this construction is to provide for the adjustment of the guide section 7 to an inner position shown in full lines in Fig. 1 for use with small or ten inch records, and to an outer position shown in 25 dotted lines for use in conjunction with larger or twelve inch records so that when the needle N has traversed inwardly toward the center of the disc and completes the playing of a record, then it will be lifted by 30 the lip 3, as will be explained hereinafter, and when the bridge plate 2 is turned with the disc D, the lifted needle will traverse the top plane face of the guides 2 and 7 and be carried outwardly to the position shown in 35 Fig. 1 and dropped from the dropping off end 7^c in proximity to the initial groove of the record so that the needle will be automatically replaced to repeat.

To smooth out any sharp angles that may 40 be produced by the angular adjustment of the adjustable guide section 7 about its pivot 6, a flexible guide strip or track 8 is provided to reach across the end of the guide section 2 and onto the contiguous pivoted 45 end of the adjustable section 7.

Means are provided for fastening the 50 guide sections in relatively adjusted position, and such means may comprise a slotted arm 9 secured to the inner side of the adjustable section 7 and curved concentric to the pivot 6 and reaching under a tie or brace 10 connecting the cross piece 4 and the outer end of the bridge plate 2. Passing through the tie or brace 10 and the 55 slotted arm 9 is a frictional clamp screw 11.

In operation, the transferring bridge or 60 plate 2 is deposited on top of the record disc D and is centered on the turntable pin P, and the sound box needle N of the reproducer is positioned at the outermost groove of the record on the disc, and at this time the needle is in free sliding engagement with a stop bar 13 having, preferably a straight edge against which the needle will 65 bear and along which the needle slides

gradually inward while it follows the spiral record groove. Therefore, the needle serves as means for holding the transferring bridge plate 2 against rotation with the disc upon which it rests and is preferably provided 70 with soft foot pads 12, as of felt.

The stop bar 13 is here shown as being adjustably connected as by a pivot 14 provided on the outer end of the adjustable cam or guideway section 7, the object of the pivotal adjustment being to enable the stop bar 13 to be positioned substantially radial as to the pin P when the adjustable guideway section 7 is in its inner or in its outermost positions. Means are also provided for substantially automatically locking or yieldingly latching the adjustable stop bar 13 in one or another of its two positions, and such means is clearly shown in the underneath plan, Fig. 3, as including a finger 15 having 85 a lug on its outer end which is adapted to spring into one or another of sockets or indentations provided on the contiguous bottom face of an outwardly extending flange 7^d of the section 7.

In the playing of the larger records, it is desirable to shift the stop bar 13 inwardly so as to provide a suitable effective length for supporting the needle end while it is traversing the spiral groove centripetally, 95 and, therefore, the stop bar 13 is here shown as being slidably mounted on the primary part or carrying arm 13^a.

Preferably, the device is slightly overbalanced so as to tilt when free of the needle end downwardly on the lip side 3 to insure the bridge passing in under the needle when this is positioned at the inner end of the record groove and clears the inner end of the stop bar 13, and the bridge plate is, therefore, tiltable on a line radially from the center pin P of the table through a fulcrum pin F provided on the outwardly extending bracket arm 4^a. Therefore, while the needle N is in engagement with the stop bar 13, it ends to tilt, under the resistance of the needle downwardly, but as soon as the needle clears the inner end of the stop bar 13 the overbalanced lip side of the bridge plate is free to fall a slight degree down 115 toward the record so as to be in position to sweep under the needle as the lip edge 3 swings in the direction of the arrow a around to the needle N after the bridging plate has been released from the needle and is then free 120 to be carried with the turning record upon which it rests. As soon as the leading lip 3 of the bridging plate picks up the needle the latter enters the guideway between the side flanges 2^a and 2^b, and one or the other of 125 these, as the case may be, serves as a cam to shift the needle N with the tone arm of the phonograph out to the adjustable guideway section 7, and this in turn carries the needle still further out until it is deposited 130

over the drop off end 7^c back onto the outer portion of the record, spiral groove in such position as to immediately begin reproducing.

5 A feature of the invention consists in the provision of means with the guide plate for automatically stopping the rotation of the record and the turntable when so desired, and in Figs. 1, 2 and 5 the stopping means 10 includes a brake block 20 secured in a downwardly turned arm 21 which is pivoted at 22 on the outturned flange 7^d of the guideway 7. The brake lever arm 21 is normally thrown to an outer position so as to clear 15 the contiguous peripheral edge of the disc D, but when it is desired to stop the disc and turntable, the brake lever arm 21 with the brake block 20 is adapted to be adjusted inwardly toward the rim of the disc and to be 20 effectually applied automatically, after it has been so adjusted, by the needle N. For this purpose the brake lever arm 21 has an inwardly extending lever arm or handle portion 23 projecting over the flange 7^d of the 25 guideway section 7 and being of such length as to extend across the guide flanges 7^a and 7^b as is shown in dotted lines in Fig. 1. When so inwardly disposed, it will be seen that after the needle has traversed the 30 complete record and is picked up by the lip 3 of the guide plate, the latter throws the needle N outwardly until it abuts against the inwardly adjusted striking lever 23 and this serves to instantly set the brake block 35 20 against the rim of the disc and, therefore, stops rotation of the same.

I have shown in Fig. 6 a slightly modified form of the automatic stopping device that is adapted for attachment to repeating devices, such as have already been completed and are in use. In this form the brake lever 40 21 is pivoted on a block 25 adapted to be applied under the flange 7^d of the repeater, and over the top of this flange there is 45 adapted to be snapped a clamp leaf or finger 26 secured to the block 25 and providing a space for the reception of the guideway flange, as clearly shown in Fig. 6.

Further embodiments, modifications and 50 changes may be resorted to within the spirit of the invention as here claimed.

What is claimed is:

1. In a repeating attachment for a phonograph, a main plate provided with a needle-

lifting blade and comprising one section of 55 a guideway formed in two sections capable of relative movement.

2. In a repeating attachment for a phonograph, a main plate provided with a needle-lifting blade and comprising one section of 60 a guideway formed in two sections capable of relative movement, said sections being pivotally connected.

3. In a repeating attachment for a phonograph, a main plate provided with a needle-lifting blade comprising one section of a guideway formed in two sections capable of relative movement, and means comprising a frictional clamp screw extending through a 65 brace for securing said sections in an adjusted relationship. 70

4. In a repeating attachment for a phonograph, a main plate provided with a needle-lifting blade and comprising one section of 75 a guideway formed in two sections capable of relative movement, there being a needle engaging stop pivotally mounted at the end of one of said sections.

5. In a repeating attachment for a phonograph, a main plate provided with a needle-lifting blade and comprising one section of a guideway formed in two sections capable of relative movement, there being a needle engaging stop at the end of one of said sections to adapt the same to records of different widths, and said needle engaging stop being adapted to a corresponding adjustment. 80

6. In a repeating attachment for a phonograph, a main plate provided with a needle-lifting blade and comprising one section of a guideway formed in two sections capable of relative movement, the outermost of said sections carrying means capable of adjustment to stop said machine. 90

7. In a repeating attachment for a phonograph, a main plate provided with a needle-lifting blade comprising one section of a needle guideway adapted to cam said needle toward the periphery of a record, and means comprising an arm capable of extending across said guideway for preventing movement of said record relatively to a needle guided thereby. 100

In testimony whereof I have signed my 105 name to this specification.

STERRETT E. McNULTY.
